UNITED STATES PATENT OFFICE

CHARLES A. MOORE, OF EDINA, MINNESOTA

VENTILATING, REFRIGERATING, AND DEHUMIDIFYING APPLIANCE

Application filed August 9, 1930. Serial No. 474,284.

This invention relates to ventilating, refrigerating and dehumidifying appliances of the general type disclosed in Patent No. 1,777,573, granted to me October 7, 1930, and in my copending application Ser. No. 474,285, filed August 9, 1930.

An object of the present invention is to secure, in addition to the benefits secured in the appliances of the above mentioned patent and application, a more effective refrigerated recirculation of the air within the enclosure and to obtain greater flexibility in operation.

More specifically, it is an object of my present invention to provide an air conditioning appliance for establishing and maintaining a refrigerated recirculation of air within a chamber, in which appliance the relatively warm air from the upper portion 15 of the chamber, as well as the colder air from the lower portion of the chamber, is received therein and effectively cooled and thereafter passed on to the circulating flow of air in the chamber proper at its elevation of beginning, either at the upper portion of the chamber or at the lower portion thereof, as the case may be.

The various further objects will more fully appear from the detailed description 30 and the novel features will be particularly pointed out in the claims.

In the drawings, Fig. 1 is a side elevational view of an appliance embodying my invention installed in a chamber to be refrigerated and ventilated; Fig. 2 is a vertical sectional view, taken as on the line 2-2 of Fig. 3; Fig. 3 is a plan view, and Fig. 4 is a vertical sectional view in detail taken as on the line 4-4 of Fig. 3.

Referring to the drawings, it will be observed that I have illustrated fragmentarily a building structure forming a chamber X, said structure including a floor 5, side walls 6 and ceiling 7. Within this building structure I have illustrated an appliance embodying my present invention, the same including three upright conduits. Portions of these conduits being concentrically disposed, they may be conveniently referred to as inner, intermediate and outer conduits.

The outer conduit includes a refrigerant pipe 10 coiled turn upon turn, the turns of said pipe being slightly spaced apart to permit of the reception between them of bolts 13, which clamp the coiled pipe 10 between paired straps 12 and upright standards 11, the latter having their footing upon a base ring 8 of angle iron disposed over a floor drain 9. At the lower end of the pipe coil is a skirt 38 which is secured to the standards 11 by bolts 38^a. The upper margin of this skirt 38 encircles the lower turn of the pipe 10, the end of which projects through the skirt and connects with a valved pipe fitting 10^a. The lower edge of the skirt 38 terminates considerably short of the floor 5 leaving a way opening into the outer conduit from the lower portion of the chamber. Capping the upper end of the pipe coil is a hood 14 formed with a depending flange 15 which is clamped between the outer face of the upper turn of the coiled pipe 10 and the inner faces of the inturned flanges of the standards 11, the end of the upper turn of the pipe 10 projecting through said skirt and being connected with a valved pipe fitting 10^b. The hood 14 is of frusto-conical form, and issuing therefrom is an elbow 26 connecting with a vertical branch pipe 27, which terminates at its upper end near the ceiling 7 of the chamber and which is fitted at that end with a damper 39. Issuing outwardly from said vertical branch pipe 27 is a horizontal branch pipe 28 flared at its outer end as at 29, said flared end 29 supporting a thimble 29^a. Within this thimble is mounted a fan 30 driven through a belt 30^a from a motor 31 secured to the lower side of said thimble.

The intermediate conduit consists of an upright pipe 21 fitted at its upper end with an inclined extension 20. This extension connects with an elbow 19 issuing from the hood 14 in diametrically opposed relation with respect to the elbow 26 of the outer conduit. Connecting with said elbow 19 is a vertical branch pipe 18 which opens at its upper end near the ceiling 7 of the chamber and which is fitted at that end thereof with a damper 40. Extending outwardly from the vertical

branch pipe 18 is a horizontal branch pipe 16, the same passing through a side wall 6 of the building structure and being fitted with a damper 34.

The inner conduit consists of a vertical pipe 36, the upper portion of which passes through the upper part of the extension 20 of the intermediate conduit and through the peak of the hood 14, the upper end of said pipe 36 terminating at an elevation near the ceiling 7 of the chamber X and being fitted at that end with a damper 46. The lower end of pipe 36 connects with a horizontally disposed branch pipe 37 at a point between the ends thereof, diametrically opposed notches 38^b being cut in the skirt 38 to receive the upper portion of said branch pipe 37. One end of this branch pipe 37 is extended through a wall 6 of the building structure and is fitted with a damper 42, the other end of said branch pipe 37 being covered with a removable cap 41.

Between the inner walls of the coil formed by the pipe 10 and of the hood 14, on the one hand and the outer walls of the pipe 21 and extension 20, on the other hand, are a pair of partition plates 24 and 25 which are arranged in a common plane diametrically of the concentric conduits. These partition plates form within the outer conduit two upright passageways 22 and 23, the passageway 23 being in communication at its upper end with the upper portion of the chamber X through elbow 26 and pipe branches 27 and 28. Said passageway 23 also communicates with the upper portion of the chamber through an elbow 44 issuing from the hood 14 and connecting with an upright branch pipe 43 terminating at its upper end near the ceiling 7 of the chamber and fitted at such end with a damper 45. The other passageway 22 communicates at its upper end with the upper portion of the chamber X through an elbow 33 issuing from the hood 14 and connecting with an upright branch pipe 32 terminating at its upper end near the ceiling 7 of the chamber and fitted at such end with a damper 35.

The lower end of the pipe 21 and the lower turn of the coiled pipe 10 occupy positions at substantially the same level.

50 The pipe connections 10^a and 10^b, respectively connected with the lower and upper ends of the coiled pipe 10, are connected, respectively, with the feed and return leads, not shown, communicating with a source of refrigerant supply, such as brine or the like.

With the refrigerant passing through the coiled pipe 10, the turns thereof become frosted together, rendering the wall of the outer conduit solid between the skirt 38 and hood 14. From this appliance, air may be blown by the fan 30 into the upper portion of the chamber, such air consisting of air drawn upwardly through the outer conduit from the floor of the chamber and/or air from the ceiling of the chamber and/or air from the outer

atmosphere drawn downwardly through the intermediate conduit and thence upwardly through the outer conduit. And, by virtue of the partition plates 24, 25 and the passageways 22 and 23 formed thereby in the outer 70 conduit, the air that is blown into the upper portion of the chamber by the fan 30 may further consist of air drawn downwardly from the ceiling of the chamber through passageway 22, thence upwardly to the fan 75 through passageway 23. In this connection, it is to be noted that a part of the air being recirculated passes from the ceiling of the chamber into the appliance and from the appliance back into the upper portion of the 80 chamber after having twice traveled the length of the refrigerating coil, first downwardly in passageway 22 and thence upwardly in passageway 23.

Without the fan 30 in operation, fresh air 85 from the outside may gravitate into the lower portion of the chamber through the intermediate conduit. And air recirculating, may descend from the upper portion of the chamber to the lower portion thereof through the passageway 22 by way of the branch pipe 32, and through passageway 23 by way of branch pipe 43 and/or branch pipe 27, and through the intermediate conduit by way of the branch pipe 18 and through the inner 90 conduit by way of the branch pipe 37.

In any case, whether the fan is in operation or not, air may be exhausted to the outside through the inner conduit.

Among the particularly advantageous features residing in the present structure is the feature of air recirculation, through the appliance, from the upper portion of the chamber and back to such portion thereof, and the further feature of conducting varying 100 quantities of air downwardly through the appliance by way of the several valved avenues for such travel of air from the upper to the lower portion of the chamber.

In passing through the appliance, and particularly the outer conduit thereof, the air is dehumidified to a greater or lesser extent and thus conditioned in such respect before entering upon its circulatory passage 110 through the chamber proper.

Changes in the specific form of my invention, as herein disclosed, may be made within the scope of what is claimed without departing from the spirit of my invention.

Having described my invention, what I 120 claim as new and desire to protect by Letters Patent is:

1. The combination with a structure forming a chamber, of an appliance therein comprising an upright refrigerated conduit, a second upright conduit within the first conduit, partition means between said conduits forming therebetween two upright passageways communicating at their upper ends with the upper portion of the chamber, the 125

- second conduit being in communication at its upper end with the outer atmosphere, a third upright conduit within said first conduit opening at its upper end into the upper portion of the chamber and at the lower end thereof into the outer atmosphere, and means for impelling air upwardly through one of the passageways into the upper portion of the chamber, the action of such air impelling means serving to draw air into the said passageway from the lower end of said second conduit and similarly from the other passageway.
2. The combination with a structure forming a chamber, of an appliance therein comprising an upright refrigerated conduit, a second upright conduit within the first conduit, partition means between said conduits forming therebetween two upright passageways, the same being in valved communication at their upper ends with the upper portion of the chamber, the second conduit at its upper end being in valved communication, selectively, with the outer atmosphere and with the upper portion of the chamber, said second conduit and said passageways at the lower ends thereof being open to the interior of the chamber at its lower portion, and a third upright conduit within said first conduit, the same, at its lower end, being in valved communication, selectively, with the outer atmosphere and with the lower portion of the chamber.
3. The combination with a structure forming a chamber, of an appliance therein comprising an upright refrigerated conduit, a second upright conduit within the first conduit, partition means between said conduits forming therebetween two upright passageways communicating at their upper ends with the upper portion of the chamber, the second conduit at its upper end being in valved communication, selectively, with the outer atmosphere and with the upper portion of the chamber, means for impelling air upwardly through one of the passageways into the upper portion of the chamber, the action of such impelling means serving to draw air into the said passageway from the lower end of said second conduit and similarly from the other passageway, and means for the egress of air from the room.
4. In combination with a structure forming a chamber, an appliance therein comprising an upright refrigerated conduit communicating at the lower end thereof with the lower portion of said chamber, partition means within said conduit forming therein two upright passageways communicating at their upper ends with the upper portion of the chamber, means for impelling air upwardly through one of the passageways into the upper portion of the chamber, the action of such impelling means serving to draw air into the said passageway from the lower portion of the chamber and similarly from the other passageway.
5. In combination with a structure forming a chamber, an appliance therein comprising an upright refrigerated conduit, partition means traversing the interior of said conduit and forming therein two upright passageways communicating at their upper ends with the upper portion of the chamber, means for impelling air upwardly through one of the passageways and forcing it horizontally along the upper portion of the chamber, the action of such impelling means serving to draw air into the said passageway from the lower end of the other passageway.
6. In combination with a structure forming a chamber, an appliance therein comprising an upright refrigerated conduit, partition means within said conduit forming therein two upright passageways communicating at their upper ends with the upper portion of the chamber, means for impelling air upwardly through one of the passageways into the upper portion of the chamber, the action of such impelling means serving to draw air into the said passageway from the lower end of the other passageway.
7. The combination with a structure forming a chamber, of an appliance therein comprising an upright refrigerated conduit communicating at its lower portion with the lower portion of said chamber, a second upright conduit within the first conduit, partition means between said conduits forming therebetween two upright passageways communicating at their upper ends with the upper portion of the chamber, the second conduit being in communication at its upper end with the outer atmosphere, said second conduit and said partition means terminating at their lower extremities short of the lower end of said first conduit, means for impelling air upwardly through one of the passageways into the upper portion of the chamber, the action of such impelling means serving to draw air into the said passageway from the lower end of said second conduit and similarly from the other passageway and from the lower portion of the chamber, and means for the egress of air from the chamber.

In testimony whereof I affix my signature.
CHARLES A. MOORE.
